(57) **CLAIM**

The ornamental design for a buffer tube insert, as shown and described.

DESCRIPTION

FIG. 1 is a side plan view of the buffer tube insert showing our new design;

FIG. 2 is a top plan view of the buffer tube insert of FIG. 1; FIG. 3 is a bottom plan view of the buffer tube insert of FIG. 1;

FIG. 4 is an end plan view of the buffer tube insert of FIG. 1; and,

FIG. 5 is an opposite end plan view of the buffer tube insert of FIG. 1.

1 Claim, 1 Drawing Sheet
